UNITED STATES PATENT OFFICE.

MAX ANDERS EKLOF, OF CHICAGO, ILLINOIS.

FORM-SUPPORTING DEVICE.

Application filed May 26, 1928. Serial No. 280,869.

My invention relates to form supporting devices and more particularly to devices for use in building constructions to effectively support forms or molds employed for associating concrete and cement with the steel structural work.

In general my invention contemplates the provision of a supporting device of simple and economical construction which includes a keeper member adapted to engage the work with which it is associated, said keeper being provided with struck out portions for receiving supporting strips, said struck out portions being designed to effectively cleat the strip in position with respect to the keeper in response to the application of pressure to the struck out portion.

More specifically an object of my present invention resides in the provision of a supporting device which includes a keeper member comprising a plate having a portion struck out of the plane of the plate and adapted to permit the threading therethrough of supporting strips and being further adapted to firmly secure or cleat the strip in position upon the keeper member in response to the application of sufficient pressure to cause the crimping of said strip adjacent the struck out portion.

Another object of my present invention is to provide a supporting means of simple design including a keeper member comprising a plate or body portion having a work engaging portion formed along the margin of the body portion, said body portion being struck out to form a cleat adapted to receive a supporting strip or member, and being further adapted to effect the crimping of the associated strip in response to the application of a sharp blow, thereby firmly connecting the supporting strip with said keeper.

It is a further object of my invention to provide a device of the instant nature which is particularly adaptable for use in connection with building constructions and to this end I propose to provide a keeper member which is designed to grip the flange portion of steel beams and the like and which is provided with a struck out portion adapted to receive strips employed to properly associate a form or mold with the work, said keeper being so constructed and arranged as to permit of the convenient tightening of said supporting strips during the association of the form with the work and being further designed to effect the crimping of the strip in

response to the sharp blow of a hammer or the like, to thereby effectively interlock the strip with said keeper.

A still further object of my present invention resides in the provision of a supporting device for forms and the like employed in building construction, said device comprising a keeper member which may be formed from a flat strip of metal, said keeper being formed at one end thereof with a hook portion for engaging the flange of a steel beam and another portion adapted to rest upon the outer surface of a beam flange, said portion being provided with cleats struck out of the plane of the stock and adapted to permit the convenient threading of mold supporting strips therethrough and designed to interlockingly engage or cleat said strip with respect to the keeper upon the application of a blow which is sufficient to cause the crimping of the portion of the strip passing through said cleat.

In addition to the above mentioned advantageous characteristics, my invention further contemplates the provision of a form supporting device for building constructions and the like which includes a keeper adapted to be positioned at any point along the external surface of the flange of a beam, one end of the keeper having a hook portion for engaging the edge of said flange and struck out cleat portions provided in said keeper for receiving and securing a form supporting strip in position, and another keeper member adapted to engage the outer surface of a form and the outer extremity of said form supporting strip so as to effectively control the lateral positioning of the form with respect to the beam.

These, and other objects will be more apparent from the following detailed description when considered in connection with the accompanying drawing, wherein:

Figure 1 is a plan view of my improved supporting device shown in operative association with an I beam and a form or mold associated therewith for receiving concrete;

Figure 2 is an enlarged vertical transverse sectional view taken along the line 2-2 of Figure 1;

Figure 3 is a similar transverse sectional view taken along the line 3-3 of Figure 1;

Figure 4 is a perspective view of the keeper and a form supporting strip shown in operative association therewith, prior to the crimping of said strip;

Figure 5 is a central longitudinal sectional view of the keeper and strip shown in Figure 4, after the strip has been crimped in response to the application of a blow upon 5 response to the application of the keeper;

Figure 6 is an enlarged perspective view of the form engaging keeper member, a form supporting strip being shown in association with the keeper prior to the crimping thereof; and

Figure 7 discloses a modified or alternative form of the invention for use in connection with U beams.

Referring now to the drawing wherein like numerals have been employed to designate similar parts throughout the various figures, it will be observed that one embodiment of my invention resides in the provision of a keeper member indicated generally by 15 the numeral 2, Figure 4, which may be constructed of suitable sheet material, preferably steel. This keeper member comprises a body or plate portion 4 which is formed at one extremity with a hook portion 6 designed 20 for engaging the edge of a flange 8 of a structural beam 10. The body portion 4 of the keeper member is provided with struck out portions or cleats 12 and these cleats are adapted to readily permit the threading 25 therethrough of a strip 14 which is used for supporting forms or molds 16 as clearly 30 shown in Figures 1 and 2.

The form 16 which I have disclosed merely for purposes of illustrating a practical application of my improved supporting device, comprises side walls 18 and a suitable base portion 20 as shown in Figure 2. In order to facilitate the initial proper positioning of the form 16 with respect to the beam 10, I provide suitable members 22 which extend inwardly from the walls 18 of the form and similar members 24 which extend upwardly from the base 20 of the form. When the form is initially carried into association 40 with the beam 10, these members 22 serve to effect the proper lateral positioning of the form and the members 24 serve to properly space the base of the form with respect to the bottom of the beam. It will be observed that 45 the strips 14, which are of suitable metallic construction, may be threaded through apertures 26, Figure 2, provided along the base 20 and the upper extremities thereof threaded through the struck out portions or cleats 50 12 of the keepers 2 positioned on the upper flange of the beam, Figure 1. By merely applying a sharp blow as by means of a hammer to the cleat 12 of one of the keepers, the strip 14 will be crimped in the manner 55 shown in Figure 5 so as to effectively interlock said strip and cleat. After this one extremity of the strip has been secured to its companion keeper in the manner just described, the opposite extremity of the strip 60 65 may be gripped by any suitable or conven-

tional strip tightening means (not shown). When said strip has been sufficiently tightened, a sharp blow may similarly be applied to the cleats of the other keeper thereby rendering both extremities of the strip secured to their respective keepers so as to effectively support the form 16. Experience has shown that by securing the strip to the keepers in the manner described, relative movement between said parts is positively precluded, and in fact the gripping action of the cleat is sufficient to withstand any force or stress to which the strip may be subjected. From the foregoing it will be observed that in associating the keepers with the beam and in subsequently cleating the strip in position, there is no longitudinal movement of the keepers with respect to the beam and hence said keepers may be initially positioned in proper spaced relationship 80 along the beam. In other words, the force which is applied to the keepers for the purpose of securing the same to the extremity of the strips is applied transversely of the beam and not longitudinally thereof, thereby precluding the possibility of any shifting movement of the keepers longitudinally of the beam with which they are associated.

From the foregoing description, it will be understood how I employ my improved keeper members for securing the extremities of a strip which is passed through the bottom portion 20 of the form and it will also be observed that I employ certain of said keepers for supporting the form in proper lateral position with respect to the beam. In this connection I employ a keeper indicated generally by the numeral 2^a, Figures 1 and 6, which includes a body portion 4^a simulating the body portion 4 of the keeper 2 shown in Figure 4. The keeper 2^a is also provided with struck out portions or cleats 12^a which function similarly to the cleats 12 of the keeper 2 and one extremity of the keeper 2^a is provided with flanges 28 which are designed to engage the outer surface of a horizontal strip 30 which forms a portion of the side wall structure of the form 16. The extremity of one of the strips 14 is first threaded through the cleats 12^a and a sharp blow applied to said cleats in order to crimp the strip and secure the same in position with respect to the keeper and the opposite extremity of the strip is then threaded through the side wall of the form and then through the cleats 12 of one of the keepers 2 which is positioned with its hook portion 6 in engagement with the flange 8 of the beam. By gripping the inner extremity of the strip adjacent the keeper 2 in a suitable manner, the flanges 28 of the keepers 2^a will be carried into engagement with the outer surface of the strip 30, and when the strip has been sufficiently tightened, the cleats 12 of the keeper 2 may be struck so as to crimp the 100 105 110 115 120 125 130

strip, thereby effecting the proper lateral position of the form with respect to the beam. Obviously a strip having another of the keepers 2^a secured to the extremity thereof 5 of may be passed through the opposite wall of the form 16 and the inner end of said strip secured to another of the keepers 2 which engages the opposite flange portion of the beam. From the foregoing it will be apparent 10 that the tightening of the strips will serve to effectively and securely position the form in proper relation with respect to the beam to permit of the introduction of concrete or cement into the form. The strips in 15 this instance not only serve as effective means for supporting the form, but also as reinforcing structure for the concrete or cement (not shown) which is associated with the form.

In instances where beams of the **U** type 20 are employed, I propose to use the keeper 2^b shown in Figure 7. This keeper 2^b merely presents a duplication of the keeper 2 shown in Figure 4 or in other words is twice as wide as the keeper 2. The keeper 2^b is provided 25 with cleats 12^b and a hook portion 6^b which is adapted to engage the flange of the beam in a manner similar to that described in connection with the use of the keeper 2. From Figure 7 it will be apparent that the keeper 30 2^b presents a unitary device for securing both extremities of the strip 14. In use, the strip is threaded through the bottom of the form and through the cleats 12^b of the keeper similarly to the manner described in connection 35 with the association of the strip of the keepers 2 upon the **I** beam 10. After the strip has been thus positioned, one of the extremities thereof is secured to the keeper 2^b by applying a blow or pressure to the cleats companion to said extremity. A force may then 40 be applied longitudinally of the strip by gripping the opposite extremity thereof and the cleats companion to said extremity may be tightened thereagainst.

From the foregoing description it will be apparent that my invention provides a very convenient means of simple and economical construction for anchoring the extremities of supporting strips and the like. The keepers 50 which I have described may be formed from flat malleable stock because of the unitary construction thereof. My device is adaptable for use in supporting conventional types of forms with a minimum degree of effort and skill and the firm gripping or cleating effect 55 which is produced when the struck out portions of the keeper are subjected to the blow of a hammer so as to crimp the supporting strips, serves to positively secure the form in proper position. In fact, after the strip has 60 been crimped by the cleats of the keepers the strength of the gripping effect thus produced exceeds the tensile strength of the strip material. As hereinbefore set forth, the keepers 65 are not subjected to the lateral forces during

the application thereof to the beams and hence the possibility of shifting said keepers longitudinally of the beam during the assembling operation is precluded. Thus said keepers may be distributed in predetermined spaced 70 relation along the beam and obviously this feature greatly facilitates the uniform distribution of form supporting structures along the beam.

It is to be observed that in tightening the 75 keepers in position upon the beams, as for example the types shown in Figures 4 and 7, the outer vertical surface of the hook portion of the keepers provides an abutment for the tool (not shown) which is employed to so subject the strips to tension. In other words, when the strip 14 is engaged by the conventional tool and urged to the right as viewed in Figure 5, said tool may be brought to bear against the hook portion of the keeper. In 85 this manner the strip is pulled in one direction and the keeper is secured in position by reason of the engagement of the tool therewith in the opposite direction. Thus the outer surface of the hook portion of the keeper 90 is adapted to provide a bearing surface for the conventional tool which is employed to tighten the strip.

Although I have disclosed and described my improved keeper member in connection 95 with a particular structure, namely, a mold for **I** and **U** beams, it will be apparent that keepers constructed in accordance with the teachings of my invention are capable of many other applications and modifications 100 without departing from the spirit and scope of the appended claims.

Having thus described my invention, what I claim as new and desire to secure by Letters Patent is:

1. In a supporting device of the class described, a keeper member having one portion adapted to interlock with the work and another portion struck out of the plane of the keeper stock for receiving a supporting strip 110 and adapted to cleat said supporting strip in position.

2. In a supporting device of the class described, a keeper member having one portion adapted to interlock with the work and another portion struck out of the plane of the keeper stock for receiving a supporting strip and adapted when force is applied thereto to crimp the supporting strip and thereby effectively secure said strip to the keeper. 115

3. In a supporting device of the class described, a keeper member having one portion adapted for anchorage with the work and another portion struck out from the plane of the keeper stock in one direction and adapted to crimp a supporting strip associated therewith when force is applied in a direction opposite to the direction in which the portions are struck out from the keeper. 120

4. In a supporting device of a class de- 130

- scribed, a keeper member having a portion adapted for anchoring engagement with the work and another portion struck out of the plane of the keeper stock so as to present 5 a loop through which a supporting strip may be threaded, said loop being adapted to effect the crimping of said strip when a force is applied thereto.
5. In a supporting device of the class described, a keeper member comprising a body portion, a portion formed angularly with respect to the body portion for engagement with the work, and a cleat on the body portion for receiving a supporting strip and 10 adapted to crimp said strip when a force is applied to the cleat.
6. In a supporting device of the class described, a keeper member comprising a body portion, a portion formed angularly with respect to the body portion for engagement with the work said body portion being provided with a malleable loop for receiving a supporting strip and adapted when force is applied thereto to crimp the strip material, 15 thereby effectively securing said strip material to the keeper.
7. In a form clamp, a strip for inter-connecting the form and another member such as a beam, and a keeper having a body portion provided with cleats extending out of the plane of the keeper stock, said cleats adapted when strip material is associated therewith, to crimp said strip material in response to the application of a force to the 20 cleat, said keeper having a lateral portion for engaging the work.
8. In a form clamp, a keeper comprising a body portion adapted to engage the outer surface of a beam flange and another portion for engaging the edge of the flange, said body portion being formed with cleat members struck out of the plane thereof and adapted to receive a supporting strip and to 25 secure said strip in position upon the application of a force to the cleat members.
9. In a supporting device of the class described, a keeper member constructed of flat, malleable stock and having a portion struck out of the stock to present a cleat, said cleat being adapted upon the application of sufficient force to be deformed and to thereby grip a member associated therewith so as to 30 secure said member against movement relative to the keeper; said keeper having a lateral portion for engaging the work.
10. In a device of the class described, a keeper member having a malleable cleat for receiving a strip of material, the malleable characteristic of said cleat serving to render the same deformable in response to the 35 application of a force thereto which is sufficient to crimp the associated portion of the strip material, thereby securing said strip against longitudinal displacement with respect to the keeper, said keeper having a lateral portion for engaging the work.
11. In a form supporting device of the class described, a keeper member having a body portion of malleable flat stock, said body portion being provided with a struck-out section for receiving a form supporting strip and adapted, when force is applied thereto, to crimp said strip, thereby effectively securing said strip to the keeper, the body portion of said keeper being provided with a lateral 40 section formed integral therewith for engaging the work so as to secure said keeper in proper position for application to the work.
12. In a form supporting device of the class described, a unitary keeper member having one portion adapted to interlock with the work and another portion struck-out of the plane of the keeper stock for receiving a supporting strip and adapted, when force is applied thereto, to crimp the supporting strip and thereby effectively secure said strip to the keeper, the interlocking portion of said keeper providing a surface against which a strip tightening tool may bear when tension is being applied thereby to the strip.
13. In a form supporting device of the class described, a unitary keeper member having a body portion adapted to engage the work, said body portion being provided with a lateral portion adapted to interlock with the work so as to secure the keeper in proper position upon the work, said body portion being provided with sections struck-out of the plane of the keeper stock, one of said sections adapted to receive one terminal of a supporting strip and another of said sections adapted to receive the opposite end of said supporting strip, whereby when force is applied to said struck-out sections, the extremities of said supporting strip may be effectively secured to the keeper.
14. In a form supporting device of the class described, a keeper member having a body portion provided with sections struck-out of the plane of the keeper stock for receiving a supporting strip and adapted, when force is applied thereto, to crimp the supporting strip and thereby effectively secure said strip to the keeper, said keeper being further provided with a flange extending laterally with respect to the body portion and adapted to engage a surface of the form to be supported thereby.
- In witness whereof, I have hereunto subscribed my name.

MAX ANDERS EKLOF.
